**CEILING WIPER FOR EMBEDDING TAPE
AND FOR REMOVING EXCESS MASTIC
FROM WALLBOARD JOINTS**

Robert G. Ames, Hillsborough, Calif., assignor, by mesne assignments, to Ames Taping Tool Systems Manufacturing Co., Harvey, Ill., a corporation of Delaware
Filed Jan. 29, 1962, Ser. No. 169,492
5 Claims. (Cl. 15—104.8)

The present invention relates to improvements in a ceiling wiper for embedding tape and for removing excess mastic from wallboard joints and it consists in the combinations, constructions and arrangement of parts hereinafter described and claimed.

A broad knife can be used for removing excess mastic while embedding a joint covering tape in mastic on a ceiling, but this necessitates the use of scaffolding so that the operator can stand on it and reach the ceiling. Moreover the broad knife will scrape excess mastic from the joint, but the mastic has a tendency to slide along the scraper blade and then drop onto the operator's hand or face or onto the floor where it must be removed before it sets. The blade cannot hold any appreciable quantity of excess mastic it has scraped from the joint and this necessitates the operator to repeatedly stopping and cleaning the blade.

The principal object of my invention is to provide a ceiling wiper for embedding tape and for removing excess mastic from wallboard joints in which the handle is made hollow and constitutes a receptacle for receiving excess mastic. A hopper is associated with the scraper blade and will receive excess mastic scraped off by the blade and will deliver the mastic to the interior of the handle for temporary storage. The handle can be of a desired length for holding the excess mastic and an arm is attached to the hollow handle for providing sufficient length to the device for permitting an operator to stand on the floor and move the blade against the joint on the ceiling that is to be wiped down, removing excess mastic therefrom.

It is necessary to remove the excess mastic from the hollow handle and I therefore mount a piston in the cylinder and connect a piston rod thereto. The arm that extends from the lower end of the barrel has a piston rod retaining member provided with an opening for receiving the outer end of the piston rod when the latter is extended from the barrel and the piston is at the lower end of the barrel.

A modified form of the device omits the arm that extends beyond the lower end of the cylindrical barrel. The cylindrical barrel is made longer and the piston rod is in two parts with a coil spring or other pivotal connection between the parts permitting the outer part of the piston rod to be swung into parallel position with the barrel and be clamped thereto when the piston is at the lower end of the barrel or at its starting position.

The device is simple in construction. The scraper blade is centered in a hopper so that mastic moving down either surface of the blade will be received in the hopper. The hopper in turn directs the mastic into the interior of the cylindrical barrel.

Other objects and advantages will appear as the specification continues. The novel features of the invention will be set forth in the appended claims.

Drawings

For a better understanding of my invention, reference should be made to the accompanying drawings, forming part of this specification, in which:

FIGURE 1 is a front elevation of the device;

FIGURE 2 is a longitudinal transverse section through

2

the device and is taken along the line 2—2 of FIGURE 1;

FIGURE 3 is a section through the hopper and part of the cylindrical barrel; these parts being inclined so as to incline the mastic-scraping blade at the proper angle with respect to the joint mastic and tape being scraped and embedded;

FIGURE 4 is a front elevation of a modified form of the invention; and

FIGURE 5 is a longitudinal transverse section through the modified form and shows the two part piston rod with its two portions in alignment with each other and the piston moved into its extreme discharge position.

While I have shown only the preferred forms of my invention, it should be understood that various changes, or modifications, may be made within the scope of the annexed claims without departing from the spirit thereof.

In the covering of wall board joints in the ceiling, the abutting edges of two adjacent pieces of wall board forming the joint are covered with a layer of mastic and a strip of tape is embedded in the mastic. The present tool is used for embedding the tape in the layer of mastic and for smoothing it and removing any excess mastic.

Detailed Description

In carrying out my invention I provide a ceiling wiper for removing excess mastic and for embedding the tape in the mastic layer. This tool has a cylindrical barrel A adapted to retain mastic that has been scraped off from the joint. At the top of the cylindrical barrel I mount a hopper or receptacle B and this hopper has a rear wall 1 that is in the shape of an inverted truncated triangle. The rear wall has integral side walls 2 and 3 that extend at right angles to the rear wall and at an angle to each other. The side walls 2 and 3 flare outwardly from a base or a bottom wall 4. FIGURE 2 shows the side walls of less width at their upper edges 2a and 3a than at the edges disposed adjacent to the base 4. The base has an integral depending collar 5 and this collar slips over the top of the cylindrical base A and may be secured to the barrel by welding or any other suitable fastening means.

The hopper carries a mastic scraping blade C of the shape shown in FIGURE 1 and this blade is spaced from the rear wall 1 of the hopper by a spacing and blade-supporting block D. Bolts 6 extend through the blade C, the spacing block D and the rear wall 1 of the hopper B and are used for securing the blade C to the hopper B. Any other suitable fastening means may be used for securing the blade to the spacing block.

It will be noted that the outer edge 7 of the flexible scraping blade has a length slightly less than the outer edge 1a of the rear wall 1. The side edges 8 and 9 of the blade are curved toward each other as they extend away from the outer edge 7 and the sides terminate at an inner edge 10. The inner edge 10 parallels the outer edge 7 of the blade. The portion of the blade extending beyond the spacing block D is free to flex when the tool is being used. A small front wall 16 has its lower edge contacting the front edge of the base 4 and has its ends secured to the side walls 2 and 3.

Within the cylindrical barrel A, I mount a piston E and this piston is shown in dotted lines in its lowermost position in FIGURE 1 and in dot-dash lines in an upper position in the same figure. In FIGURE 2 the piston E is shown at the bottom of the barrel A and the barrel is provided with an inner ring F at its lower end that will hold the piston from being withdrawn from the barrel. The ring F may be secured to the lower end of the barrel by screws 11 or any other suitable fastening means.

At the top of the cylindrical barrel A the base plate 4 for the hopper B has an opening 4a that is slightly less in

diameter than the inner diameter of the cylindrical barrel A. Therefore the base member 4 will act as a stop for the piston E when the latter is moved by a piston rod G to the top of the cylindrical barrel A. In this manner the piston E can be moved the entire length of the barrel by the piston rod G, but the piston cannot accidentally be moved out of the barrel A.

I provide a support for the free end 12 of the piston rod G when the piston is at its lowermost position in the cylindrical barrel A. The support comprises an elongated arm H that is secured to a pair of circular bands J by bolts 13. The circular bands J are secured to the lower end of the cylindrical barrel A and may be welded or otherwise attached to the outer surface of the barrel. The arm H parallels the piston rod G and the arm carries a piston rod retainer K at its outer end. FIGURE 1 shows the piston rod retainer provided with an opening 14 for removably receiving the free end of the piston rod when the latter is in its lowermost position i.e. when the piston E is at the bottom of its stroke and bears against the inner edge of the ring F.

Operation

From the foregoing description of the various parts of the device, the operation thereof may be readily understood. The cylindrical barrel A is about two and one-half feet long and about two and one-half inches in diameter although I do not wish to be confined to this exact measurement. The purpose of the barrel is to receive mastic that has been scraped from the joint L shown in FIGURE 3 and the mastic thus scraped will be guided into the hopper B by the blade C and then will pass through the opening 4a in the bottom wall 4 of the hopper and into the barrel A. The capacity of the barrel is sufficient to hold a quantity of mastic that is scraped from a joint and the lineal footage that can be covered by the scraper is about two hundred and forty feet before the barrel A is filled and needs emptying. Again I do not wish to be confined to any exact number of feet of mastic that may be scraped before the barrel A will be filled with mastic because this will vary according to the amount of excess mastic removed and the capacity of the barrel. The advantage of the device over the usual hand trowel is that the operator can use it for a considerable period of time and will not be subjected to the annoyance of having the scraped off mastic falling onto his hands or face or splattering upon the floor where it will have to be subsequently removed. Also the operator will not have to stop every few feet to remove the mastic from the blade which would be true if only a hand trowel were used.

The spacing of the blade C from the rear wall 1 of the hopper provides a unique passage between the blade and rear wall for receiving and guiding any removed mastic into the lower part of the hopper where it will pass through the opening 4a and into the barrel interior. It will further be seen that the spacing of the side walls 2 and 3 of the hopper B from the side edges 8 and 9 of the blade C will provide passages between these walls and the adjacent blade edges for receiving excess mastic and for guiding it into the barrel A.

The barrel A is made about two and one-half feet long and then the supporting rod H is connected to the barrel and will extend substantially two and one-half feet beyond the lower end of the barrel so that the combined lengths of the barrel and arm H will give sufficient overall length to the tool so that the operator may grasp the tool while standing on the floor and bring the scraping blade C into contact with the joint mastic L that is on the ceiling. This will permit the device to be used in rooms having ceilings eight to eleven feet in height above the floors. If the usual hand trowel were used instead of my tool, the operator would have to use scaffolding on which to stand. The cost of the scaffolding and the time required to erect it and to move it from place to place adds considerably to the cost of the operation.

FIGURE 3 shows the barrel A inclined slightly from the vertical so that the blade C will contact with the joint mastic L at an angle which will permit the operator to scrape excess mastic from the joint. The arrows 15 shown in FIGURE 3 indicate the flow of excess mastic that has been scraped from the mastic layer L and is flowing into the cylindrical barrel A. During the operation of the tool, the free end 12 of the piston rod G will be received in the opening 14 provided in the piston rod retainer K. Therefore the piston rod G will be held in parallel relation with the arm H. The operator may grasp the barrel A with one hand and he may grasp the arm H or the arm and the piston rod G with the other hand. It is easy for the operator to grasp the device at a place along the barrel A and along the arm H which will permit him to move the blade C into contact with the joint mastic L that has been applied to the ceiling of the room.

When the barrel A becomes filled with mastic or if at any time the operator desires to empty the barrel of mastic, the operator can grasp the piston rod G and move the piston rod into the barrel for causing the piston E to move toward the opening 4a and expel the mastic therethrough. During this movement the end 12 of the piston rod will first be removed from the opening 14 in the piston rod retainer K and then the piston rod moved for moving the piston E. The hopper B can be placed over a bucket or any other kind of container that is to receive the mastic ejected from the barrel A by the movement of the piston E. After the mastic has been emptied from the barrel the tool can be used again.

Modified Form of the Tool

In a modified form of the tool shown in FIGURES 4 and 5, the barrel A, the hopper B, the scraper blade C and the spacer D are all identical to the form shown in FIGURES 1, 2 and 3 and therefore similar letters and numerals will be given to corresponding parts. The arm H is not used in the modified form of the device and the jointed piston rod M takes the place of the rigid piston rod G. The cylindrical barrel A may be made longer in the modified form of the device than is the barrel A in the form shown in FIGURES 1 to 3 inclusive. The purpose of this is to provide a longer hand grip portion since the arm H is not used in the modified form and furthermore the longer barrel A can hold a greater quantity of mastic before the device needs to be emptied.

The piston E is mounted on a short piston rod M' and this short piston rod is connected to the longer piston rod M by a coil spring connector N. The tendency of the coil spring connector N is to assume a straight line when freed and therefore the connector will hold the piston rod M in axial alignment with the short piston rod portion M'. The coil spring connector N will permit the piston rod M to be swung into a position paralleling the axis of the cylindrical barrel A and lying outside of the barrel. A spring clamp P is secured to the outer surface of the cylindrical barrel A and removably receives the end of the piston rod M when the latter is swung substantially through an arc of 180° into the position shown in FIGURE 4. The piston E will be at the bottom of the barrel A when the piston rod M extends along the outer surface of the cylinder A. The operator can grasp the barrel A and use it as a handle for moving the outer edge 7 of the blade C into contact with the joint mastic L on the ceiling. The device can be used in the same manner as that explained for the form of the device shown in FIGURES 1, 2 and 3. The portions M and M' constitute a jointed piston rod.

When the operator wishes to empty the mastic from the barrel A, he frees the piston rod M from the clamp P and the coil spring connection N will immediately swing the piston rod M into alignment with the short piston rod portion M'. The operator can move the piston rod M into the barrel A and this will move the piston E into the cylindrical barrel for forcing the mastic through the

opening 4a and into the hopper B, see FIGURE 5. The tool can be held in a position where the hopper B will deliver the mastic into a bucket or other receptacle.

I claim:

1. A tool of the type described comprising: 5
  - (a) a cylindrical barrel open at each end;
  - (b) a hopper mounted at one end of the barrel and having an opening in its base communicating with the adjacent open end of the barrel;
  - (c) a flexible blade;
  - (d) means for supporting the blade so that its lower end is received in the hopper and its outer end extends beyond the hopper; said means spacing said blade from all of the inner surfaces of said hopper;
  - (e) a piston slidably mounted in the barrel and normally positioned in the barrel at the end opposite to the end that has the hopper connected thereto; and
  - (f) a piston rod connected to the piston for moving it through the barrel for expelling mastic therefrom.
2. The combination as set forth in claim 1: and in 10 which
  - (a) piston rod supporting means is connected to the cylindrical barrel and supports the outer end of the piston rod when the piston is disposed at the end of the barrel opposite to the hopper;
  - (b) said piston rod supporting means constituting an extension to the barrel which may be grasped by an operator when using the tool to embed tape in a layer of mastic on a ceiling.

3. The combination as set forth in claim 1: and in 30 which
  - (a) the hopper has sides that flare outwardly from the base of the hopper and are spaced from the adjacent edges of the blade; and
  - (b) the hopper has a rear wall that is spaced from 35

the blade and lies parallel thereto;

(c) whereby the rear wall and the flared sides of the hopper are spaced from said blade to provide a hopper whose inner surfaces will receive material removed by said blade and will deliver this material to said barrel.

4. The combination as set forth in claim 1: and in which

(a) an arm is secured to the barrel and extends beyond the barrel end furthest removed from the hopper;

(b) said arm paralleling the axis of the barrel and paralleling the axis of the piston rod; and

(c) a piston rod retainer carried by the free end of the arm and having an opening therein for receiving the outer end of the piston rod.

5. The combination as set forth in claim 1: and in which

(a) the piston rod is in two parts a short part and a long part, with a coil spring interconnecting the parts;

(b) the short part of the piston rod being connected to the piston, and the long part being swingable into a parallel arrangement with the outer surface of the barrel when the piston is at the end of the barrel furthest removed from the hopper; and

(c) a clamp on the barrel for receiving the end of the long part of the piston rod.
